F. PFABE

TOBACCO PIPE CLEANER

Filed Aug. 1, 1921

FIG. 1.

FIG. 2.

Inventor

Fritz Pfabe

R. Haadany

Attorney.

UNITED STATES PATENT OFFICE.

FRITZ PFABE, OF LEIPZIG-SCHLEUSSIG, GERMANY.

TOBACCO-PIPE CLEANER.

Application filed August 1, 1921. Serial No. 488,766.

To all whom it may concern:

Be it known that I, FRITZ PFABE, of Leipzig-Schleussig, Germany, a citizen of the German Republic, have invented certain new and useful Improvements in Tobacco-Pipe Cleaners, of which the following is a specification.

The object of this invention is to provide an improved appliance for easily and effectively removing the incrustation which is formed on the inside of the bowls of tobacco pipes.

To this end I provide a plurality of resilient rasps attached at one end to a handle, the other ends diverging from each other, with their rough operative surfaces outwards, these operative ends of the rasps being more or less curved or dished to accommodate themselves to the interior of the pipe bowl, against which they are held, when in use, by the elasticity of the material.

I may form the handle with a socket or passage for a picker or cleaning rod for the stem of the pipe, and may shape this handle so that it can be used for pressing down the tobacco in a pipe bowl.

Around the shanks of the rasps I may place a slidable ring, which draws the rasps closely together when slid towards their operative ends, when the appliance is not in use.

The invention is illustrated in the annexed drawing, in which:—

Fig. 1 is an elevation of the appliance, and

Fig. 2 a vertical section thereof, with a pipe bowl indicated by broken lines.

In the drawing *a* designates the handle, into which are fitted the shanks of three

springy rasps *b*, whose normal position, 40 when they are not under restraint, is as indicated by broken lines in Fig. 1. A ring *c* embraces the shanks of these rasps, enabling them to be drawn together as shown in Fig. 1. When the ring is pushed up, and the 45 rasps are inserted into a pipe bowl *d*, as shown in Fig. 2, the elasticity of the shanks holds the dished heads of the rasps tightly against the wall of the bowl, which can be cleaned by turning the rasps.

A cleaning rod or picker *e* fits into a hole 50 in the handle *a*, from which it can be withdrawn for use, and the handle is shaped so that it can be used for pressing down the tobacco in a pipe bowl.

What I claim as my invention and desire to secure by Letters Patent of the United States is:—

A tobacco pipe cleaner comprising a handle having a cavity therein extending 60 lengthwise from one end thereof to within a short distance of the other end, a plurality of rasps having elastic shanks extending into said cavity and fixed to the handle at the base of said cavity, said rasps being 65 dished and integral with said shanks, a slide- 70 able ring embracing said shanks, enabling the divergent ends of said rasps to be contracted, and a removable pipe picker fitting into said handle and extending through said cavity between the shanks of the rasps.

In witness whereof I have signed this specification in the presence of two witnesses.

FRITZ PFABE.
